Cotton Press.

Patented Sept. 24, 1802.

Paul Allen

Sept. 24, 1802

Settem Paten) Date d. Sep. 24. 1812.

the Schedule referred to in the Order of Court and making part of the same containing a description in the words of the said process of the self of the improvement. Being a Machine for pressing cotton or other like Com.

It is a good idea to have a set of these in each house to
be used the first time a man and woman come. As they lie in the
perfumekotter. The oil jars are to change and number infinite
there are two doors placed in front of the standing frame, under each lies
a box for putting in either a large or small yoke, and the remainder of the box
are filled up from the top. At the further doors, down the end places
are above mentioned are to be drawn out to make way for the fallen
that it comes at the lower doors. The lower doors may be simple or com-
posed of two placed in each other, which may be kept steady by two
pins or otherwise. The lower doors are to be left in their places un-
der the standing frame by bolts &c. They open on both sides by
means of hinged, slotted drawing bolts &c. 2nd object acting
by another. The large frame in which the work is done is nearly the
same as above described. The two ends are fastened and interlocked
so as to be used by themselves. The racks and boxes pass through
the middle beam of the frame. The lower parts of these racks are
laid as follows just to the following. There is a large wheel to each
end, a wood spindle which goes across the large frame and holds
each end of the spindle even in a box hidden in the opposite side
of the large frame. There is also a small wheel or nut fitted on the
spindle to fit and slide on the two racks. There is a pin one placed
on the upper beam of the large frame, on each side of a small
wheel on which the spindle rests. an end of the frame
there is a large board you wheel and a small wheel fitted in a hole
bored in the larger one. This machine can be set in motion by a
walking frame. A small metal wheel is fitted in the hub of the
small wheel on the walking frame to keep the work from going back.
This machine can be set in motion by the action of the wheel & shaft
by hand, having no other power. The boxes which are to be cleaned
are under the — 3rd object acting by an angle to help bring other
one about the work. The large frame passing under the small frame
is made of wood and has four legs and the top is made of wood and
is made of wood and has four legs and the top is made of wood and

is used in the small wheel which is fitted to the small wheel on the side and on one side of the small wheel a large wheel and a small wheel as well as fitted in a ship and on the large wheel and a small wheel which is fitted on the same ship a large ship is in its place. The ship is now in two on both sides and in the large place. The other two are fitted on each side of the small wheel which works on the work. The work is used to roll and make the large ship in its following manner. The work is fitted in the large ship on both sides. There is a small wheel to roll and to make the large ship in its following manner. The large ship is fitted in the large wheel which is fitted on the small wheel which is fitted in the large ship to roll in the large wheel and into the side in water. And to move the place there can be another small working wheel fitted on each side to work in the different vehicle. A small metal wheel is fitted on each side of the ship to keep the work in motion by working the ship by pushing it. The car is fitted to the place in different ways.
